UNITED STATES PATENT OFFICE.

MALCOLM CAMPBELL, OF WOONSOCKET, RHODE ISLAND, ASSIGNOR TO WOONSOCKET MACHINE AND PRESS COMPANY, OF WOONSOCKET, RHODE ISLAND, A CORPORATION OF RHODE ISLAND.

SLUBBER OR FLY-FRAME.

976,545.

Specification of Letters Patent. Patented Nov. 22, 1910.

Application filed October 16, 1908. Serial No. 458,087.

To all whom it may concern:

Be it known that I, MALCOLM CAMPBELL, of Woonsocket, in the county of Providence and State of Rhode Island, have invented 5 certain new and useful Improvements in Slubbers or Fly-Frames, of which the following is a specification.

This invention has relation to spinning machines, and more particularly to fly 10 frames or slubbers.

It has for its object to provide an improved and simple mechanism for transmitting power from the compound to the bobbin driving shafts, so that they will be rotated 15 evenly and without variation or lost motion during the traverse of the bobbins. To this end, I employ a sprocket chain for transmitting power from the compound or driver to an intermediate shaft arranged in parallel- 20 ism with the bobbin shafts, and I mount said shaft in a radius arm whose axis of oscillation is coincident with the axis of one of the bobbin driving shafts. A gear on the intermediate shaft intermeshes with and drives a 25 gear on one of the bobbin shafts; and the chain is kept taut by any suitable means as by the tension of a spring which exerts its stress upon the radius arm.

Referring to the accompanying drawings, 30 Figure 1 represents a portion of a slubber embodying my invention. Fig. 2 represents a front elevation of the same. Fig. 3 represents a plan view of the mechanism which embodies the invention. Fig. 4 represents 35 a section on the line 4—4 of Fig. 1. Fig. 5 represents a section on the line 5—5 of Fig. 4.

Referring to said drawings, *a* indicates the driver from which power is transmitted to the bobbin shafts. It is illustrated as a 40 shaft having thereon, a sprocket wheel *b*. The bobbin driving shafts are indicated at *c* and *d* respectively, and they together with the rail *e*, are reciprocated vertically upon guides *e'* by the usual mechanism. To distinguish these two shafts, I designate the 45 shaft *c* as a rear shaft and the shaft *d* as the front shaft. On these two shafts *c* and *d*, are secured equal gears *f* and *g*, which intermesh as shown in Fig. 1, so that said 50 shafts are caused to be driven one from the other in opposite directions.

h indicates a cylindrical bearing in which the front bobbin driving shaft is journaled, said bearing having a flange *h'* by which

it is attached to the rail *e* as shown in Fig. 55 4. Upon this bearing is journaled a hub *j'* of a radius arm *j*, said arm having at its end lateral tubular extensions *j*² to constitute a bearing for what I term an intermediate shaft *k*. Upon one end of this shaft 60 *k*, is journaled a pinion *k'* which intermeshes with and drives a gear or pinion *d'* on the shaft *d*. On its opposite end, the shaft *k* has a sprocket wheel *m* between which and the sprocket wheel *b* is stretched an endless 65 sprocket chain *n*. A coiled spring *o* of sufficient strength is placed upon the hub *j'* of the radius arm, one end thereof being secured to the flange *h'* of the bearing, and the other end, which is extended, being 70 passed through an aperture in the web of the radius arm as shown in Fig. 2. This spring serves to take up any slack in the sprocket chain and to hold it taut, and at the same time it permits said radius arm to 75 swing about its axis of movement as the bobbin rail is reciprocated vertically. By mounting the radius arm on an axis coincident with the axis of the front bobbin shaft, I am able to gear the intermediate 80 shaft directly to said front bobbin driving shaft by means of the straight spur gearing and effect rotation of the bobbin shafts in the proper directions.

Having thus explained the nature of my 85 said invention and described a way of constructing and using the same, although without attempting to set forth all of the forms in which it may be made, or all of the modes of its use, I declare that what I claim is: 90

1. In a spinning machine, a driver, a vertically movable bobbin shaft, a radius arm pivoted on the axis of said bobbin shaft, an intermediate shaft mounted in the free 95 end of said radius arm, intermeshing gearing for transmitting power from said intermediate shaft to said bobbin shaft, and means for transmitting power from said driver to said intermediate shaft.

2. In a spinning machine, a driver, a vertically movable bobbin shaft, a radius arm pivoted on the axis of said bobbin shaft, an intermediate shaft mounted in the free end of said radius arm, intermeshing gearing for transmitting power from said intermediate shaft to said bobbin shaft, a sprocket wheel on the driver, a sprocket wheel on 100 said intermediate shaft, a chain connecting 105

said sprocket wheels, and means for maintaining said radius arm in a position to take up the slack of said chain.

3. In a spinning machine, a driver, a vertically movable bobbin shaft, a radius arm pivoted on the axis of said bobbin shaft, an intermediate shaft mounted in the free end of said radius arm, intermeshing gearing for transmitting power from said intermediate shaft to said bobbin shaft, a sprocket wheel on the driver, a sprocket wheel on said intermediate shaft, a chain connecting said sprocket wheels, and a spring exerting a tension on said radius arm to take up the slack in said chain.

4. In a spinning machine, a driving sprocket wheel, a driven sprocket wheel, a

chain connecting them, front and rear vertically movable bobbin shafts, gearing connecting said bobbin shafts, a radius arm pivoted to move about the axis of the front bobbin shaft, an intermediate shaft mounted in the free end of said radius arm and carrying the driven sprocket wheel, power transmitting mechanism connecting said intermediate shaft with the front bobbin shaft, and means engaging said arms for preventing said chain from becoming slack.

In testimony whereof I have affixed my signature, in presence of two witnesses.

MALCOLM CAMPBELL.
